[57] CLAIM

The ornamental design for a barbering bag, as shown and described.

DESCRIPTION

FIG. 1 is a perspective view of a barbering bag, showing my new design, in an open position;

FIG. 2 is a front left perspective view of the closed barbering bag;

FIG. 3 is a left side view thereof;

FIG. 4 is a top plan view thereof;

FIG. 5 is a right side view thereof;

FIG. 6 is a bottom plan view thereof;

FIG. 7 is a front view thereof; and,

FIG. 8 is a rear view thereof.

The broken line portions of the drawing disclosure are for illustrative purposes only and form no part of the claimed design.
